WEB SUPPLY MECHANISM FOR PRINTING
PRESSES

Howard M. Barber, Pawcatuck, Conn., assignor to
C. B. Cottrell & Sons Company, Westerly, R. I.,
a corporation of Delaware

Application February 21, 1939, Serial No. 257,583

20 Claims. (Cl. 242—58)

This invention relates to web supply mechanisms of the automatic roll replenishing or flying paster type where the expiring roll web is pasted to the replenishing roll web without stopping the operation of the press.

The object of this invention, broadly, is to provide means whereby an automatic web roll replenisher may be used in connection with a web fed printing press of the flat sheet delivery type.

The object of my invention, more specifically, is to provide web sheet cutter controlled electric means for synchronizing the operation of the web roll replenisher with the operation of the sheet cutters whereby the cutters will cut off the sheet from the web at a point spaced from the free or unpasted tail end of the expiring web.

In flying pasters the pasted joint between the expiring web and the replenishing web necessarily leaves a free or unpasted tail end as the expiring web is severed from its roll. Where the operation of the web roll replenisher is not synchronized with respect to the sheet cutters of the press the sheet cutters often cut the sheet from the web at the free or unpasted tail end beyond the pasted joint, thereby leaving a loose piece of paper which tends to choke the cutters and interfere with the piling of the sheets. It is to obviate this condition that the present invention is directed.

A practical embodiment of my invention is represented in the accompanying drawing, in which

Fig. 1 represents in detail side elevation so much of a web fed printing press of the flat sheet delivery type as will illustrate the application of my invention thereto;

Fig. 2 represents a diagrammatic view of the means for synchronizing the operation of the flying paster of the web roll replenishing mechanism with the sheet cutters of the printing press;

Fig. 3 represents a detail view showing the pasted joint between the expiring roll web and the replenishing roll web after the expiring web has been severed from its roll.

The expiring web roll is denoted by W and the replenishing web roll by W'. The coating rotary cutters of the web fed flat sheet delivery printing press are denoted by 1, 2, and their knives by 3, 4. The coating rollers 5, 6 serve to direct the web between the sheet collecting rotary carrier 7 and its pressure roll 8. This sheet collecting rotary carrier 7 is herein shown as being provided with three sets of equally spaced grippers 9.

The sheet transfer rotary carrier 10 is herein shown as provided with two sets of equally spaced sets of grippers 11 which coact with every second set of grippers 9 on the sheet collecting rotary

carrier 7 to take a collected group of sheets therefrom.

The horizontally disposed flat sheet traveling endless delivery carrier 12 is shown as provided with a plurality of equally spaced grippers 13 arranged to take the collected groups of sheets from successive grippers 11 of the sheet transfer rotary carrier 10.

A sheet tail end engaging mechanism 14 of any well known or approved form is shown for taking the groups of sheets from the grippers 13 of the endless delivery carrier 12 and depositing them flat on the delivery pile 15.

The web roll replenishing mechanism may be of any well known or approved form, that shown herein comprising a rotatable frame suitable for supporting three web rolls and for bringing them successively into their pasting and replenishing position. It is to be understood that the paste may be applied in the usual manner to the surface of the replenishing web roll W', and that the roll may be rotated in the usual manner, not shown herein, for bringing the roll up to the desired speed and for bringing the paste applied portion around into position to be pasted to the expiring web W as the web is severed from its roll.

The paster comprises the pressure applying brush 16 carried by the spring pressed lever 17 which normally holds the brush in its retracted position to permit the web W to freely pass to the press spaced from the periphery of the replenishing roll which carries the web W'.

The web severing knife 18 is carried by the spring pressed lever 19 which normally holds the knife out of its operative position.

The means which I have shown for synchronizing the operation of the web replenishing mechanism with respect to the operation of the coating rotary cutters 1, 2 of the press may be electrically operated, and comprises the following elements: A rotary cam 20 may be mounted on any shaft running in a predetermined relation to the cutters 1, 2; or it may be mounted on one of the shafts of the rotary cutters, so as to rotate one revolution for each revolution of the cutters. In the present instance the cam 20 is fast on the shaft 21 of the rotary cutter 2. The cam controlled switch 22 is operated by one arm of a spring pressed rock lever 23, the other arm of which lever carries a stud or roller 24 which rides on the face of the cam 20, which cam has an extended low surface 25 for opening the switch 22 when the stud or roller 24 travels along said low portion. This switch 22 is 10- 55

cated in the main circuit A, A'. A hand switch 26 is also provided in the main circuit A, A'.

Three cams, 27, 28, 29, are mounted as a unit in a position where their axis will be coaxial with the shaft 30 of the replenishing web roll when the roll is brought to its replenishing position. Well known or approved means, not shown herein, are provided for locking the cams 27, 28, 29 to and releasing them from the said shaft. It will be understood that when the cams are locked to the replenishing web roll shaft 30 for the pasting operation the cams must all bear a fixed relationship to the key 31 of said replenishing web roll shaft and that the cams will then rotate together with the shaft and roll carried thereby. When the cams are unlocked from the shaft they will be silenced and will remain inoperative until used with the next succeeding replenishing web roll. The cam 27 controls the action of the switch 32 operated by one arm of the spring pressed lever 33, the other arm of which lever carries a stud or roller 34 which rides on the surface of the cam 27 and is operated to close the switch in the circuit A by a protuberance 35 on the face of said cam 27.

The switch 36 is operated by one arm of a spring pressed rock lever 37, the other arm of which lever carries a stud or roller 38 which rides on the face of the cam 28.

30 The switch 39 is operated by one arm of a spring pressed rock lever 40; the other arm of said lever carries a stud or roller 41 which rides on the face of the cam 29.

35 A switch 42 is operated by one arm of the spring pressed rock lever 19 which also carries the expiring web severing knife 18.

An electromagnet 43 controls the operation of the switch 42 and also the operation of the web severing knife 18; and an electromagnet 44 controls the operation of the brush depressing lever 17.

An electromagnet 45 is located on the relay 46 and an electromagnet 47 is located on the relay 48.

45 It will be noted that the rock lever 23 which carries the control switch 22 is pivoted on one arm of a rock lever 49 pivoted on the shaft 21, the other arm of which lever is connected by a rod 50 to one arm of a rock lever 51, the other arm of which is moved by a governor 52 driven from the press or delivery, as, by means of the bevel gears 53, 54 and shaft 55. This arrangement will cause the switch to be advanced or retarded around the control cam 20 to compensate for the time lag in the various relays and switches which is uniform at all speeds which compensate for varying speeds of the press. In practice, the parts are so positioned that the control switch 22 will operate at the correct time for the lowest running speed at which a paste will be made and, as the speed of the press increases, the governor will act to move the switch lever against the rotation of the cam shaft; thereby making the operation of the switch 60 enough earlier to bring the pasted joint in correct relationship with respect to the cut. This means will thus automatically regulate the time for starting the pasting operation.

70 When it is desired to paste the tail end of the web of the expiring roll W to the advance end of the web from the replenishing roll W', the replenishing web roll will be moved to bring its shaft 30 into alignment with the fixed axis of the cams 27, 28, 29. These cams are then locked 75 to the replenishing roll W' in a predetermined

relationship to the key 31 of the shaft 30, by well known or approved means, not shown herein as hereinbefore pointed out. The rotation of the replenishing roll W' to bring its paste carrying surface into position to be engaged by the web of the expiring roll W by the pressure applying brush 16 will, at the same time, rotate the cams 27, 28, 29 coincidently therewith. In the meantime, the hand switch 26 has been closed.

When the replenishing web roll W' and the sheet cutters 1, 2 have arrived at positions which will ensure the pasting together of the webs at a point which will cause the cutters to miss the free or unpasted tail end of the expiring roll web, the electric circuit A, A' will be closed mechanically at the switch 22 by the action of the cutter controlled cam 28, and also closed mechanically at the switch 32 by the action of the roll controlled cam 27. This closed circuit A, A' will energize the magnet 45 of the relay 46 which in turn will close the circuits B, B'. The circuit B is the maintaining circuit for the relay 46 and it will thus keep the relay contacts closed until the circuit is opened at the switch 42 by the energization of the magnet 43 which controls the operation of the expiring web severing knife 18.

The circuit B' energizes the magnet 47 of the relay 48 when the circuit is completed by the switch 36 which is mechanically operated by the timing cam 28. The operation of the relay 48 30 closes the circuit C, which is its own maintaining circuit, and also closes the circuit C' which energizes the magnet 44 which controls the operation of the brush 16 to push the expiring web against the paste applied surface of the replenishing web at the proper time with respect to press sheet cutters 1, 2, to paste the two webs together.

The cam 29 then operates to mechanically close the switch 39 which energizes the magnet 43 to swing the lever 19 for causing the knife 18 to sever the expiring web and at the same time open the switch 42 and thereby the circuit B to open the relay 46. This breaks the circuit B' which is in series with the maintaining circuit 45 C for the relay 48. The relay 48 operates to open the circuit C', thus deenergizing the magnets 44 and 43 and thereby allowing the brush 16 and the severing knife 18 to return under spring pressure to their non-operating positions. This completes the cycle of operations.

The cams 27, 28, 29 may then be silenced by unlocking them from the replenishing roll by any well known or approved means, not shown herein.

As a condition precedent to the operation of the synchronizing mechanism it must be borne in mind that the circumference of the replenishing roll W' must bear a differential or odd relationship to the length of the sheets cut off by the sheet cutters 1, 2. If the circumference of the replenishing roll was equal to an exact number of cut-offs by the cutters 1, 2, and the paste happened to be applied to the replenishing roll in such a position that the cutters would cut through the free or unpasted tail end of the expiring roll, this relationship would never change and the cams 20 and 21 would prevent any part of the paster mechanism from operating.

It will be understood that the sequence of operations starts with the movement of the pressure applying brush 16 to force the expiring web against the replenishing web at its paste applied portion to form the pasted joint, and that this movement of the brush cannot take place until 75

the cutter controlled cam 20 arrives in the proper relationship to the free or unpasted tail end of the expiring web, so that the cutters will not cut through the same. This should be accomplished in the fewest possible rotations of the replenishing roll.

It will also be understood that when once the parts are adjusted nothing will have to be re-adjusted so long as the replenishing rolls are 10 of approximately the same circumference when brought into their replenishing position.

It is evident that various changes may be resorted to in the construction, form and arrangement of the several parts without departing 15 from the spirit and scope of my invention, and hence I do not intend to be limited to the particular embodiment herein shown and described, but what I claim is:

1. Sheet cutters for a traveling web, means 20 for joining web replenishing and expiring rolls on the run, means for severing the expiring web beyond the joint, leaving a free tail end; and synchronizing means for preventing the cutters from severing the said free tail end.

2. Sheet cutters for a traveling web, means for 25 joining web replenishing and expiring rolls on the run, means for severing the expiring web beyond the joint, leaving a free tail end; and sheet cutter controlled synchronizing means for preventing the cutters from severing the said 30 free tail end.

3. Sheet cutters for a traveling web, means for 35 joining web replenishing and expiring rolls on the run, means for severing the expiring web beyond the joint, leaving a free tail end; and electric synchronizing means for preventing the cutters from severing the said free tail end, said synchronizing means including a cam operated switch in the circuit of the electric synchronizing means and timed with the cutters.

4. Sheet cutters for a traveling web, means 40 for joining web replenishing and expiring rolls on the run, means for severing the expiring web beyond the joint, leaving a free tail end; and electric synchronizing means for preventing the cutters from severing the said free tail end, said synchronizing means including a cam timed with the cutters and a control switch in the circuit of the electric synchronizing means and operated 45 by said cam.

5. Sheet cutters for a traveling web, means 45 for joining web replenishing and expiring rolls on the run, means for severing the expiring web beyond the joint, leaving a free tail end; and electric synchronizing means for preventing the cutters from severing the said free tail end, said synchronizing means including a cam timed with the cutters, a control switch in the circuit 50 of the electric synchronizing means and operated by said cam and means for automatically changing the position of the switch with respect to its operating cam.

6. Sheet cutters for a traveling web, means 55 for joining web replenishing and expiring rolls on the run, means for severing the expiring web beyond the joint, leaving a free tail end; and electric synchronizing means for preventing the cutters from severing the said free tail end, said synchronizing means including a cam timed with the cutters, a control switch in the circuit of the electric synchronizing means and operated by 60 said cam and a web speed controlled governor for automatically changing the position of the switch with respect to its operating cam.

7. Sheet cutters for a traveling web, means for joining web replenishing and expiring rolls on the run, means for severing the expiring web beyond the joint, leaving a free tail end; and electric synchronizing means for preventing the cutters from severing the said free tail end, said synchronizing means including a cam operated switch in the circuit of the electric synchronizing means and timed with the cutters and cams operated by the replenishing roll. 10

8. Sheet cutters for a traveling web, means for joining web replenishing and expiring rolls on the run, means for severing the expiring web beyond the joint, leaving a free tail end; and electric synchronizing means for preventing the cutters from severing the said free tail end, said synchronizing means including a cam timed with the cutters, a control switch in the circuit of the electric synchronizing means and operated by the cam and cams operated by the replenishing roll. 15

9. Sheet cutters for a traveling web, means for joining web replenishing and expiring rolls on the run, means for severing the expiring web beyond the joint, leaving a free tail end; and electric synchronizing means for preventing the cutters from severing the said free tail end, said synchronizing means including a cam timed with the cutters, a cam operated switch in the circuit of the electric synchronizing means, means for 30 automatically changing the position of the switch with respect to its operating cam and cams operated by the replenishing roll.

10. Sheet cutters for a traveling web, means for joining web replenishing and expiring rolls 35 on the run, means for severing the expiring web beyond the joint, leaving a free tail end; and electric synchronizing means for preventing the cutters from severing the said free tail end, said synchronizing means including a cam timed with the cutters, a cam operated switch in the circuit of the electric synchronizing means, a web speed controlled governor for automatically changing the position of the switch with respect to its operating cam and cams operated 40 by the replenishing roll. 45

11. Sheet cutters for a traveling web, means for joining web replenishing and expiring rolls on the run, means for severing the expiring web beyond the joint, leaving a free tail end; and electric synchronizing means for preventing the cutters from severing the said free tail end, said synchronizing means including a cam timed with the cutters, a control switch in the circuit of the electric synchronizing means and operated by 50 the cam, cams operated by the replenishing roll and magnets for controlling the operation of the web joining and web severing means.

12. Sheet cutters for a traveling web, means for joining web replenishing and expiring rolls on 60 the run, means for severing the expiring web beyond the joint, leaving a free tail end; and electric synchronizing means for preventing the cutters from severing the said free tail end, said synchronizing means including a cam timed with the cutters, a control switch in the circuit of the electric synchronizing means and operated by the cam, a web speed controlled governor for automatically changing the position of the switch with respect to the cam, cams operated by the 65 replenishing roll and magnets for controlling the operation of the web joining and web severing means.

13. Sheet cutters for a traveling web, means for joining web replenishing and expiring rolls 75

on the run, means for severing the expiring web beyond the joint, leaving a free tail end; and electric synchronizing means for preventing the cutters from severing the said free tail end, said 5 synchronizing means including a cam timed with the cutters, a control switch in the circuit of the electric synchronizing means and operated by said cam, cams operated by the replenishing roll, magnets for operating the web joining and 10 severing means and switches operated by the last named cams for controlling the operation of said magnets.

14. Sheet cutters for a traveling web, means for joining web replenishing and expiring rolls on 15 the run, means for severing the expiring web beyond the joint, leaving a free tail end; and electric synchronizing means for preventing the cutters from severing the said free tail end, said synchronizing means including a cam timed with 20 the cutters, a control switch in the circuit of the electric synchronizing means and operated by said cam, a web speed controlled governor for automatically changing the position of the switch with respect to the cam, cams operated by the 25 replenishing roll, magnets for operating the web joining and severing means and switches operated by the last named cams for controlling the operation of said magnets.

15. A flat sheet delivery web fed printing press 30 including sheet cutters for the traveling web; a flying paster for joining web replenishing and expiring rolls, an expiring roll web severing device which leaves a free tail end beyond the pasted joint; and means for synchronizing the paster with respect to the cutters whereby the 35 cutters will be prevented from cutting through said free tail end.

16. A flat sheet delivery web fed printing press including sheet cutters for the traveling web; 40 a flying paster for joining web replenishing and expiring rolls, an expiring roll web severing device which leaves a free tail end beyond the pasted joint; and web sheet cutter controlled

means for synchronizing the paster with respect to the cutters whereby the cutters will be prevented from cutting through said free tail end.

17. Sheet cutters for a traveling web, a flying paster for joining web replenishing and expiring 5 rolls, a knife for severing the expiring roll web beyond the pasted joint, leaving a free tail end; and means for synchronizing the relative positions of the paster and severed portions of the web with respect to the cutters to prevent the 10 cutters from cutting through said free tail end.

18. Sheet cutters for a traveling web, a flying paster for joining web replenishing and expiring rolls, a knife for severing the expiring roll web beyond the pasted joint, leaving a free tail end; 15 and web sheet cutter controlled means for synchronizing the relative positions of the paster and severed portions of the web with respect to the cutters to prevent the 20 cutters from cutting through said free tail end.

19. Sheet cutters for a traveling web, a flying paster for joining a web replenishing roll having a circumference bearing a differential relationship to the cut-offs by the cutters to an expiring web roll, means for severing the expiring roll 25 web beyond the pasted joint, leaving a free tail end; and means for synchronizing the relative 30 positions of the paster and web severing means with respect to the cutters to prevent the cutters from cutting through said free tail end.

20. Sheet cutters for a traveling web, a flying paster for joining a web replenishing roll having a circumference bearing a differential relationship to the cut-offs by the cutters to an expiring web roll, means for severing the expiring 35 roll web beyond the pasted joint, leaving a free tail end; and web sheet cutter controlled means for synchronizing the relative positions of the paster and web severing means with respect to the cutters to prevent the cutters from cutting 40 through said free tail end.

HOWARD M. BARBER.
